UNITED STATES PATENT OFFICE

2,687,138

UMBRELLA

Edward Okun, New York, N. Y.

Original application October 5, 1946, Serial No. 701,509, now Patent No. 2,510,597, dated June 6, 1950. Divided and this application June 9, 1949, Serial No. 98,029

3 Claims. (Cl. 135—46)

1

This invention relates to umbrellas, and more particularly to folding umbrellas, although some of the features of the invention are applicable to non-folding umbrellas.

The general object of the present invention is to improve umbrellas, and more particularly, though not exclusively, folding umbrellas.

Some objects of the invention center about the pivotal connection between the inner ends of the ribs and the rib retainer at the end of the umbrella stick. The usual practice is to use a wire the ends of which are twisted together to secure the wire and ribs on the retainer. This requires hand labor to apply and twist the wire. The twisting weakens the wire and tends to break the same. The soft wire is not suitable for long wear. When fastening the wire in position, an extra twist may break the wire, while on the other hand, too little twist may leave the wire loose in the retainer groove. Finally, the twisted end of the wire is unsightly, and tends to cut the cloth of the umbrella. To overcome all of the foregoing difficulties is one prime object of the present invention.

A similar statement may be made in respect to the pivotal connection between the inner ends of the spreaders, and the runner which slides on the umbrella stick. These have heretofore been secured by means of a twisted wire extending around a groove on the runner, with all of the attendant difficulties previously described for the rib retainer. A further object of the present invention is to improve the pivotal connection between the spreaders and the runner, with a view to eliminating the aforesaid difficulties.

Folding umbrellas commonly employ an umbrella stick made up of telescopically related metal tubes. The handle of the umbrella may be provided with a skirt-like flange adapted to hold the rib tips close to the stick when the umbrella is closed, and to hold the rib hinges close to the stick when the umbrella is folded. This requires a number of different relative positions of the telescopic tubes, together with appropriate detent means for maintaining those positions. Spring-pressed balls have been used as a detent, with considerable attendant trouble and expense. A further object of the present invention is to retain the smooth and satisfactory operation of spring-pressed balls, while eliminating the need for separate balls and spring and retainer for holding the same.

The inner tube of the telescopic umbrella stick is closed at each end by suitable studs, the stud at one end providing a stop ledge to limit exten-

2

sion of the stick, and the stud at the other end receiving the regular handle of the umbrella. Further features and objects of the invention center about these studs and a method of securely locking them in the tube.

The present application is a division of my co-pending parent application, Serial No. 701,509, filed October 5, 1946. The parent application is directed to the rib retainer, runner, and trunnion construction, while the present application is directed to features of the tubular umbrella stick.

To accomplish the foregoing objects and others which will hereinafter appear, my invention resides in the umbrella elements and their relation one to the other, as are hereinafter more particularly described in the specification. The specification is accompanied by drawings, in which:

Fig. 1 is a longitudinal section through the upper end of the umbrella stick, with the umbrella frame in nearly fully opened condition;

Fig. 2 is a plan view of a cap which forms a part of the rib retainer and the runner;

Fig. 3 is a section taken in the plane of the line 3—3 of Fig. 2;

Fig. 4 is a plan view of the sleeve portion of the rib retainer;

Fig. 5 is a side elevation thereof;

Fig. 6 is a plan view of the sleeve portion of the runner;

Fig. 7 is a side elevation thereof;

Fig. 8 is a perspective view showing the inner end of a rib having integrally formed trunnions;

Fig. 9 is a perspective view of the inner end of a spreader having integrally formed trunnions;

Fig. 10 is a longitudinal section through the umbrella in folded condition, with the fabric omitted;

Fig. 11 is a section through the upper end of the inner tube of the umbrella stick; and

Fig. 12 is a perspective view of a detent forming a part of the invention, drawn to enlarged scale.

The particular umbrella here illustrated is a folding umbrella of the type disclosed in my prior patents, Re. 21,492, granted June 25, 1940, and 2,221,288, granted November 12, 1940, but some of the features of the invention are applicable to non-folding umbrellas, especially of the type disclosed in my Patent No. 2,221,289, granted November 12, 1940.

Referring to the drawing, and more particularly to Fig. 10, the umbrella is there shown in folded condition, with the fabric omitted, and all but two of the ribs and spreaders omitted, in order not to unduly complicate the drawing. The umbrella comprises an umbrella stick made up of

an outer tube 12, and a telescopically related inner tube 14. The end of the stick has secured thereto a rib retainer 16 to which the inner ends of the ribs 18 are pivotally secured. The ribs themselves are foldable, and comprise not only the inner ribs 18, but also outer ribs 20 which are hingedly connected to the inner ribs by means of hinges 22. The ends of the outer ribs 20 may be provided with ornamental tips 24, made, for example, of one of the known plastics. The hinges 22 have trough-shaped hinge extensions 26 the primary purpose of which is to hold the outer ribs 20 in alignment with the inner ribs 18 when the umbrella is opened. When the umbrella is folded, the hinge extensions 26 cooperate with a flange or skirt 28 on umbrella handle 30, to hold the ribs 18 close to the umbrella stick. The umbrella is opened with the aid of spreaders 32, the outer ends of which are pivotally connected to the ribs 18 at 34, and the inner ends of which are pivotally connected to a runner 36. In Fig. 10, the runner is shown in its down position, but it will be understood that it may be slid upwardly on the umbrella stick to an up position, where it is retained by means of a spring catch 38. Fig. 1 of the drawing shows the runner approaching the spring catch.

Before opening the umbrella, the umbrella stick is extended by pulling the handle 30 (Fig. 10) and with it the inner tube 14 from within the outer tube 12, this motion being limited by a stop ledge 40 formed on a stud 42 closing the upper end of the inner tube 14. The stop ledge 40 bears against a stop ledge formed by the inner end of a stop liner 44 forming a part of the outer tube 12. The stick is held in extended condition by a lock 46 (better shown in Fig. 11) carried by the inner tube 14, which lock moves out beneath the lower end of the tube 12 (Fig. 10). To prevent relative rotation of the handle and the umbrella, the lock 46 moves into one of a number of slots 48 at the lower end of outer tube 12. This locks the inner tube against rotation relative to the outer tube. At this time the tips 24 of ribs 20 are clear of the skirt 28 of handle 30, so that the umbrella may be opened. The handle 30 is screwed onto a threaded stud 50 the inner end 52 of which closes the lower end of the inner tube 14.

When the umbrella is in unfolded or extended condition, but closed, the skirt 28 of handle 30 may be used to hold the tips 24 of the ribs 20 close to the umbrella stick. For this purpose, the inner tube 14 may be slid slightly into the outer tube 12 so that the skirt 28 will surround, instead of being clear of, the tips 24, and appropriate detent means are provided to hold the tubes in that position.

In all, there are four umbrella positions to be taken care of by the disclosed mechanism. In one position the umbrella stick is fully extended and the ribs and cloth are opened by the spreaders and runners; in another, the umbrella stick is fully extended but the umbrella is closed; another position is the same, except that the handle is moved slightly to surround and hold the tips of the ribs; and in the fourth position, the ribs are folded and the stick is telescoped, as shown in Fig. 10.

Considering the invention now in detail, and referring first to Fig. 8, the inner end of the umbrella rib 18 is provided with integrally formed trunnions 60 extending in opposite directions. These trunnions act as a pivot between the rib 18 and the rib retainer 16, as is shown in Fig. 1.

The particular rib here shown is of the double spring wire type disclosed in my patents previously referred to. Such a rib is made up of spring wires 62 and 64 terminated by a sheet metal fitting 66 having parts 68 curled about and clamped on the wires 62 and 64, and having ears 70, which heretofore were simply perforated to receive a wire threaded through all of the ribs, said wire passing about a grooved runner, and having its ends twisted together, as previously mentioned. In accordance with the present invention, the sheet metal ears 70 are preliminarily drawn by appropriate dies and stamping presses to provide the hollow trunnions 60 formed integrally with the ears 70. As here shown, the outer ends of the trunnions are closed, and the inner ends are open. For purposes of the present specification, the trunnions may be thought of as formed integrally with the rib, for the end fitting 66 is itself a part of the particular kind of double spring wire rib here shown. In other words, if the rib were a single piece of metal, requiring no end fittings at all, the trunnions could be formed integrally as is the case with the spreader shown in Fig. 9.

The rib retainer 16 (Fig. 1) is made up of a cap 72 and a sleeve portion 74. The sleeve is flanged outwardly at 76, and the flange is radially slotted as indicated at 78 (Fig. 4), to receive the inner ends of the ribs, or more specifically, the ears 70 shown in Fig. 8. The flange 76 together with the cap 72 provide a bearing space therebetween for receiving the trunnions 60.

The particular rib retainer here employed is best shown in Figs. 2 through 5 of the drawings. The cap 72 comprises a top wall 80, an inner wall 82, and a rim 84, the latter being shaped to receive and hold the edge of the flange 76 as here illustrated, the rim is internally grooved at 86 to receive the edge of the flange 76. The edge of the rim 84 is preferably beveled as indicated at 88, and this, together with the slots 90, make it possible to spring the cap onto the sleeve with a snap fit. In Figs. 4 and 5 it will be seen that the edge of flange 76 may also be beveled, as indicated at 92. The sleeve is provided with means for securing it to the outer tube 12 of the umbrella stick, and in the form here shown, there are tongues 94 which slope inwardly and are received in recesses 96. In preferred form, half the tongues point downwardly, and the other half point upwardly, so that the retainer will be held against rotation, and also against axial movement on the stick. In the present example, four tongues are used.

In practice, the sleeve portion 74 of the rib retainer is preliminarily secured to the umbrella stick, and in effect forms a part of the same. The ribs are hung downwardly from the flange 76, the trunnions of each rib being supported by the flange. The cap 72 is then added, it being simply pressed downwardly with a snap fit, and thereafter operates to hold the ribs in position.

The spreader 32 may be a single heavy wire, as described in my earlier patents. The inner end of the spreader is flattened, as indicated at 100 (Fig. 9), but instead of perforating the flattened end, as heretofore, the die which flattens the same is so shaped as to leave trunnions 102 projecting in opposite directions therefrom, these trunnions being integral with the spreader. Subsequent die operations may be performed to bring the trunnions to the cylindrical shape shown.

Reverting now to Fig. 1, the trunnions 102 are received in a bearing space formed in the runner

36 previously referred to. The runner is much like the retainer in being made up of a sleeve portion 104 and a cap 106. The sleeve portion is better shown in Figs. 6 and 7, it comprising a cylindrical part of sufficient diameter to slide readily on the umbrella stick, and a flange 108. The flange is preferably made identical in dimension with that of the rib retainer, so that the same cap may be employed for both the retainer and the runner. A window 110 is cut through the sleeve 104 to receive the spring catch 38 previously mentioned. The opposite end of the sleeve is flared outwardly slightly as shown at 112, in order to facilitate sliding movement on the stick, and more importantly, in order to retain an annular finger piece 114 on the sleeve. This finger piece 114 is pushed upwardly when opening the umbrella, and is pulled downwardly when closing the umbrella. During this downward movement, the sloping inner surface 116 of the finger piece bears against the catch 38, and cams it inwardly, thereby releasing the runner for downward movement. It will be understood that both the flange 108 and the cap 106 are radially slotted and appropriately beveled and grooved to fit together with a snap engagement, all as previously described. It will also be understood that the inner ends of the spreaders are gathered together in proper position before snapping the parts of the runner together. If the spreaders have been preliminarily riveted to the ribs, as is usually the case, the inner ends of the spreaders are gathered into the cap 106, and the sleeve is then snapped into the cap.

Referring now to Fig. 10, the hinge extensions 26 are held within skirt 28 of handle 30, and for this purpose the inner tube 14 is retained in position by detent projections 118 received above the stop liner 44. The detent projections 118 are formed at the lower ends of the arms of an inverted U-shaped spring member 120 carried inside the tube 14. The projections 118 pass through diametrically opposed openings or windows 122 in tube 14.

The spring detent is best shown in Fig. 12, where it has been drawn to enlarged scale. Until pushed into and confined by the tube, the arms normally assume a widespread condition shown in broken lines at 120'. The detent projections 118 are well rounded, and are preferably narrower in width than the U-shaped portion 120. Thus adequate spring pressure may be obtained, and the detent member is better locked against possible displacement within the tube, while at the same time the detent projections 118 themselves are small, and act much like the spring-pressed balls heretofore employed. The present improvement dispenses with the need for two balls, a compression spring for the same, and retainer means to hold the spring and balls in position.

When the umbrella stick is in extended position, but the umbrella is closed with the skirt 28 of handle 30 around the tips 24 of the ribs, the inner tube 14 is held in position by engagement of another set of detent projections 124 located near the upper end of tube 14. These cooperate with the same stop liner 44. They are formed at the ends of a U-shaped member 126 identical with that already described and shown in Fig. 12. The detent projections are received in diametrically opposed windows, as already described, the sole difference being that it is convenient to insert the spring 126 through one end of the tube, and the spring 120 through the opposite end of the

tube, so that the U-shaped portions face in opposite directions.

The lock 46 (Fig. 11) is itself formed as a part of a U-shaped spring 128, and this is disposed in a plane substantially perpendicular to the plane of the spring 126, so that there is no interference therebetween. In fact, the inner edge of lock 46 may be cut away, as indicated at 130, to safely clear the U-shaped spring 126 when the lock is pushed inwardly. While the lock 46 holds the tube 14 against inward movement and against rotation, the stop ledge 40 of stud 42 holds the tube 14 against outward movement or complete removal from the outer tube. For this purpose, the stop ledge 40 is larger in diameter than the inner tube, and is large enough in diameter to bear against the stop liner 44 (Fig. 10) previously referred to.

To secure the stud 42 in the end of tube 14, the stud is peripherally grooved at 132, and the tube 14 is spun inwardly at 134 to lock the stud and tube together. This eliminates the need for a diametrical cross pin or rivet, and provides a neater, better, and less expensive connection.

The stud 52 at the lower end of the inner tube 14 is similarly grooved at 136, and the tube 14 is spun inwardly at 138 to securely lock the parts against axial movement. In this case, however, the stud is preferably longitudinally knurled or fluted as indicated at 140, before being driven into the tube, in order to further guard against any possibility of rotative movement of the stud relative to the tube. This is desirable so that the umbrella handle 30 may be screwed tightly onto the stick, and also to guard against any possibility of rotation of the handle and stud relative to the umbrella.

The stop liner 44 is secured within the outer tube 12 in any desired fashion, as by the use of tongues 142 received in mating slots in the liner. The catch 38 may be secured on the outer tube 12 in any convenient manner, as by the use of a ring 144. The ornament 146 at the end of the umbrella stick is screwed in place, it being internally threaded to mate with a thread 148 formed at the free end of the tube 12 above the rib retainer 16.

It is believed that the improved umbrella construction of my invention, as well as the advantages thereof, will be apparent from the foregoing detailed description. The use of integrally formed trunnions on the inner ends of the ribs and spreaders, together with the rib retainer and runner which are assembled around the trunnions, provides a stronger, long wearing, simplified structure. There is a substantial reduction in the labor needed to assemble the umbrella frame. Similar remark applies to the detents, which are simpler in structure, and require less labor for assembly than is the case with spring-pressed ball detents. The end studs are secured to the inner tube of the umbrella stick with less labor than with a diametrical pin, and the resulting structure is stronger than that heretofore provided.

It will be apparent that while I have shown and described my invention in one particular form, changes may be made in the structure shown, without departing from the spirit of the invention as sought to be defined in the following claims.

I claim:

1. A folding umbrella comprising a tubular metal umbrella stick, said stick having telescopically related inner and outer portions, the inner

or smaller diameter portion being provided with rounded frictional detent means cooperating with the outer or larger diameter portion to yieldably hold the stick in shortened condition, said detent means including a spring metal strip bent to U shape and disposed inside the smaller diameter portion, the ends of said U being bent reversely to form rounded detent projections, and said inner portion having a pair of diametrically opposed windows through which said detent projections project to engage a part of the outer tubular member intermediate the ends of said outer tubular member, a flat lock formed at one end of a U-shaped spring also disposed in said inner portion, the plane of said lock passing through the axis of the stick and being substantially perpendicular to the plane of the detent, said lock and said detent being so shaped and disposed as to avoid interference by the detent when the lock is pushed inward to release the same.

2. A folding umbrella comprising a tubular metal umbrella stick, said stick having telescopically related inner and outer portions, said outer stick having a stop ledge of reduced diameter near its lower end, said outer stick having an inside diameter greater than the outside diameter of the inner stick to afford room for said stop ledge, the inner or smaller diameter portion being provided with detent means including a spring metal strip bent to U shape and disposed inside the smaller diameter portion near its lower end for cooperation with the stop ledge to yieldably hold the stick in shortened condition, the ends of said U being substantially reduced in width compared to the main body of the U, and said narrowed ends being bent reversely convex-

ly outward to form rounded detent projections, and said inner portion having a pair of diametrically opposed windows through which the outermost portions only of said rounded detent projections project to engage the aforesaid stop ledge, said windows being wide enough to pass the reduced width of the ends but not the wider main body of the detent.

3. In a folding umbrella, a telescopic umbrella stick comprising a tubular metal outer portion and a tubular metal inner portion, a solid metal stud having an inner end closing the lower end of the inner portion of said stick and having a threaded portion projecting therefrom beyond the end of the stick for receiving an umbrella handle, the inner end of said stud being longitudinally knurled or fluted on its outer surface to discourage rotation, and being provided also with a peripheral groove, said tubular inner portion of said stick being spun inwardly at said groove to permanently lock the stud and tubular inner portion of said stick together.
